FUNCTION GENERATOR

Walter R. Hedeman, Jr., Baltimore, Md., assignor to Bendix Aviation Corporation, Towson, Md., a corporation of Delaware

Application September 18, 1951, Serial No. 247,046

2 Claims. (Cl. 250—27)

This invention relates generally to electric function generation and more particularly to circuits for generating inverse functions related to a mechanical motion.

Many function generators are known in the art for producing desired mathematical relationships between physical quantities. The establishment of a desired inverse functional relationship between two quantities has in the past been accomplished with relatively complex arrangements.

The primary object of the present invention is to provide a simple and economical inverse function generator.

Another object is to provide an improved function generator which is stable in operation and capable of supplying useful load current.

A further object resides in provision for adjusting the shape and relative position of the inverse function generated to satisfy varying requirements.

These and other objects of the invention are achieved by providing a controlled output voltage across an output impedance element which is under control of the voltage across a portion of the impedance. Circuit arrangements are provided whereby the control voltage across the portion of the impedance is maintained substantially constant regardless of the ratio that portion bears to the whole output impedance so long as the control range is not exceeded. Under these conditions motion imparted to a variable element to vary the ratio of the portion bears to the whole generates as the controlled output voltage an inverse analogue of the motion.

In the drawings:

Fig. 1 is a schematic diagram of a circuit of the present invention employed in an antenna system;

Fig. 2 shows a modification; and

Fig. 3 is a schematic diagram of a circuit of the invention having sensitivity and level adjustments.

Referring to Fig. 1 there is shown a variable width waveguide antenna 11 having a movable element 12 driven in oscillatory linear motion by a driving means 13. A current supply tube 14 supplies current to the series adjustable resistors R₁, R₂ and R₃ from a D. C. source 15. The high potential end of R₁ is connected to control a suitably referenced amplifier tube 16 which in turn controls the current tube 14. The value of R₁ is varied in accordance with the position of the element 12 by a suitable linkage thereto. The output voltage e_o appearing across R₁, R₂ and R₃ is applied to a utilization means such as a deflection circuit 17 of a cathode-ray tube 18.

In operation the linear movement of the element 12 causes a scanning motion of the beam of the antenna 11 which is related to the displacement of element 12 by a hyperbolic or inverse function. The linear motion (translational or angular) which varies the resistance of R₁ linearly, produces an output voltage e_o which can be made the analogue of the scanning antenna beam position as follows. The gain provided by control tube 16 is made sufficiently high to maintain the voltage e₁ essentially constant regardless of the setting of R₁ within the

2

operating range of the system. For this condition the output voltage is

$$e_o = e_i \cdot \frac{R_1 + R_2 + R_3}{R_1 + R_3} = e_i \left(1 + \frac{R_2}{R_1 + R_3} \right) \quad (1)$$

The output voltage e_o is thus composed of a constant term (e_i) and a voltage

$$e_i \left(\frac{R_2}{R_1 + R_3} \right)$$

which varies inversely with the value of R₁. This is a general form of an expression for a hyperbolic function which can be made to fit a given hyperbola by adjustment of the parameters R₂ and R₃ and the addition of a D. C. voltage for level adjustment, if required. The phase of the change in R₁ with respect to the antenna beam motion (i. e. whether R₁ increases or decreases with respect to beam motion from an arbitrarily chosen zero position) determines the sign of the functional relationship between the dependent and independent variables.

In applications where the hyperbolic term is desired free of the constant term (e_i), the voltage e_h may be utilized as the output voltage. This arrangement will, in general, be limited to small load currents to prevent any appreciable voltage drop in R₃ therefrom.

Referring to Fig. 2 a modification of the voltage divider R₁, R₂, R₃ is shown in which R₁ is constant and e_i is established across R₃ and a fractional part of R₁, namely, X R₁ where X has values between zero and unity. The resultant expressions for e_o and e_h are again hyperbolic and of the form

$$e_o = e_i \cdot \frac{R_1 + R_2 + R_3}{X R_1 + R_3}$$

and

$$e_h = e_i \cdot \frac{R_1 + R_2 - X R_1}{R_3 + X R_1}$$

In Fig. 3 a modification is shown in which R₃ is made up of two series resistances R₂+R₄. For this arrangement the expression (1) becomes

$$e_o = e_i \left(1 + \frac{R_2}{R_1 + R_2 + R_4} \right) \\ = e_i \left(1 + \frac{1}{1 + \frac{R_1 + R_4}{R_2}} \right)$$

which may be a more convenient form for adjusting the parameters to obtain a fit with a given curve. The two resistors of value R₂ in Fig. 3 are ganged to maintain their equality for all settings. The cathode of tube 16 in Fig. 3 is returned to a source of adjustable reference potential E such as an independent regulated D. C. supply 21 to provide a sensitivity adjustment controlling the available output voltage swing of e_o. The D. C. level of e_o is adjusted to any desired value by returning the voltage divider via lead 22 to a potential E_c from another suitable independent D. C. voltage source such as regulated supply 23.

The operation of the circuit of Fig. 3 in a particular case would be as follows. In an application, such as a cathode-ray tube deflection circuit drive, it is desired to drive the deflection stage from near cutoff to near grid-current voltage levels. This implies a specific voltage range of swing between specific voltage levels. The proper shape curve to fit the analogue is obtained by the choice of values of R₁, R₂, R₄, using curve fitting techniques such as obtaining a fit at two or more points by substituting values for the variables at three points and solving for the unknown values. The amplitude of voltage change is adjusted by adjusting the voltage E, since this is a "sensitivity" control. The level at which the swing starts

is then set by adjusting E_c , which is a "bias" or "level" control. The output of the device is then the desired form of signal for the particular case under consideration.

Obviously, other degenerative amplifier systems may be used to drive the output impedance combination. Such amplifiers need only to maintain substantially constant the voltage across the portion of the output impedance which supplies the input thereof for the purpose of this invention.

What is claimed is:

1. A system for producing a voltage which is an inverse function of a linear mechanical motion input, comprising: a constant voltage direct current source; positive and negative terminals associated with the said source; a triode vacuum tube; means electrically connecting the plate of the said tube to the said positive terminal; three resistors; an element associated with one of the said resistors to vary the value of the resistance thereof; said resistors being serially and electrically connected such that the said variable resistor is located in the center position thereof; means electrically connecting the said serially connected resistors between the cathode of the said tube and the said negative terminal; an amplifying tube; a fourth resistor; means electrically connecting the said fourth resistor between the plate of the said amplifying tube and the said positive terminal; a biasing means; said biasing means electrically connected between the cathode of the said amplifying tube and the said negative terminal; means electrically connecting the said plate of the said amplifying tube to the grid of the said triode tube; means electrically connecting the grid of the said amplifying tube to the terminal of said variable resistor that is electrically closer to the said cathode of the said triode tube; and means imparting a mechanical motion to said element to vary the value of the said variable resistor thereby producing a voltage variation across the said serially connected resistors which is an inverse function of the said mechanical motion.

2. A system for producing a voltage which is an in-

verse function of a linear mechanical motion input, comprising: a constant voltage direct current source; positive and negative terminals associated with said source; a vacuum tube having a plate, a cathode and at least one grid; means electrically connecting the plate of said tube to the said positive terminal; a resistance voltage divider having an intermediate point movable over a range of values for changing the ratio of the resistances of said divider on opposite sides of said point; means electrically connecting the said voltage divider between the cathode of said tube and the said negative terminal; an amplifying tube having a plate, a cathode and at least one grid; a resistor; means electrically connecting the said resistor between the plate of the said amplifying tube and the said positive terminal; a biasing means; said biasing means electrically connected between the cathode of said amplifying tube and the said negative terminal; means electrically connecting the said plate of said amplifying tube to the grid of said vacuum tube; means electrically connecting the grid of said amplifying tube to said movable point; and means imparting a mechanical motion to the said movable point to produce a voltage variation across said voltage divider which is an inverse function of said mechanical motion.
